ABSTRACT OF THE DISCLOSURE

A color screen is produced by exposing, either successively or simultaneously, a plurality of photosensitive layers to short duration, high intensity radiation actinic to each layer. The radiation is in a pattern such that an aliquot part of each layer is exposed. The layer is dyed with a selected color. The exposed areas are in side-by-side registration on a transparent backing and form a multicolor screen of general utility in the photographic arts.

CROSS REFERENCE TO RELATED APPLICATIONS

This application is a continuation-in-part of application Ser. No. 50,239, filed June 26, 1970, now abandoned, which, in turn, is a continuation-in-part of application Ser. No. 628,940 filed Apr. 6, 1971, now abandoned.

BACKGROUND OF THE INVENTION

In general, color screen elements comprise a screen pattern formed of a plurality of light-filtering, colored elements which are each of an independent color and which are generally classifiable into different groups in accordance with the colors thereof. Thus, a conventional three-color additive screen generally has a set or group of primary red-colored filter elements, a set of primary blue-colored filter elements and a set of primary green-colored filter elements. These filter elements are ordinarily arranged in a mosaic or geometrical pattern in a random or regular distribution.

The production of color screen elements, in accordance with the prior art, may be classified into two major groups.

First, color screen elements may be prepared by totally mechanical means, as for example, by printing or ruling a dyeable substrate, for example, with a greasy ink formulation, in accordance with the desired filter pattern; subjecting the substrate to suitable coloration, in areas which do not possess the repellent ink mask; effecting removal of the mask; and repeating this procedure, in accordance with the geometrical pattern of filter elements desired, a sufficient number of times to provide the desired multiplicity of diversely colored filter elements.

A second mechanical method comprises directly printing a carrier substrate with the desired dye formulations in accordance with the predetermined filter pattern and repeating this printing procedure a sufficient number of times to provide the multiplicity of colored filter elements desired.

A third mechanical method comprises depositing as an irregular filter screen pattern, a thin layer comprising a random distribution of small grains such as starch grains, which have been independently colored with the colors desired for optical filtering effects.

The second major type of color screen production procedures comprises photomechanical methods of the type proposed by, for example, Ducos Du Hauron in the nineteenth century. These procedures comprise in gen-

eral, coating a suitable support or film base with an adhesive composition having coated thereon a photosensitive colloid composition, as for example, dichromated gelatin; effecting exposure of the sensitive gelatin layer by incident actinic radiation, through a suitable mask which provides an exposure pattern devised in accordance with the desired optical filter element arrangement; effecting differential hardening of the sensitized colloid as a function of the point-to-point degree of exposure; removing unexposed unhardened gelatin by solvent contact; and then subjecting the remaining hardened colloid to a suitable dyeing procedure in order to provide a first-colored optical filter element series. This procedure is then repeated employing appropriate masks, as often as necessary to provide the number of optical filter element types desired in the final color screen element.

The preceding mechanical methods of producing color screen elements by mechanical printing or ruling methods inherently require a great number of mechanically exact printing steps to provide a finished product, and thus possess the relative high cost inevitable to such complexity of production. Because of the extreme difficulties of manufacture, and of the relative costs in general, production of color screen elements by means of these processes has been extremely limited. Only the so-called Dufay process has had an extended production duration, but, nevertheless, only a relatively limited market.

Methods of mechanically producing mosaic type color screen elements have, in general, provided elements inherently lacking in color balance, due to areas possessing a predominance of particles of one color, as a practical result of attempted random distribution. This problem of statistical clumping requires the employment of extremely fine colored grains in order that formation of random aggregates of the same color may be decreased. Attempts to avoid the problem of aggregates by this latter mechanism, however, gives rise to the additional disadvantage that the thus-prepared units then require very fine grain photographic emulsions, when employed as a component of a photographic film unit, and are thereby restricted to employment in low speed photographic processes. Furthermore, due to the necessary increase of interfaces between filter elements per unit area, color saturation is extensively decreased. Experience has also shown that attempts to prevent overlapping of respective filter units, in this system, and to correct for the lack of true juxtaposition between respective filters have been, at best, inadequate to provide color filter screens of sufficient optical acuity to attain the desired commercial significance. The only commercial process of this type having extended duration produced the so-called Autochrome plate of Lumiere. This plate comprised a mosaic of red, green and blue starch grains which were allowed to settle onto a tacky glass surface and then flattened out into tiny filter elements, each about 0.015 millimeter in diameter.

Although initially proposed almost a century ago, photomechanical methods of preparing color screen elements have singularly failed to attain commercial significance. This has been true irrespective of the fact that extensive research on such systems has been carried out during the intervening time interval.

One basic problem with regard to photomechanical systems has been encountered in producing filter elements having the physical parameters, for example, structure and color intensity, necessary to provide a commercially acceptable product.

A second, related, basic problem has been to insure that individual photosensitive areas, ultimately forming the optical filter units, are accurately subjected to substantially complete photo-exposure throughout their total prescribed area, and that any optical defects, for exam-

ple, parallax, resultant from the exposure source, be maintained at such a minimum level as to provide optical filter element boundary areas with the requisite integrity.

A third, related, problem has been to design apparatus which alleviates the first two problems by such means as will allow, in a practical manner, the continuous manufacture of color screens in sufficient quantity and with sufficient quality to attain true commercial significance.

Accordingly, it is a principal object of the present invention to provide processes particularly adapted for the photomechanical production of a color screen.

An additional object of the invention is to provide a method for making color screens of the above-described character having a plurality of sets or series of colored optical filter elements providing a screen pattern with the elements of each set being of the same color, hence possessing the same chromatic filtering properties, but different in color from the elements in any other set, by practices which reduce the processing steps heretofore required to produce such screens and which provide products of good quality at great simplicity and consequent low cost.

A further object of the invention is to provide a method by which the relative number, surface area, thickness, and color intensity of individual color elements comprising the color screen may be varied within and/or from screen to screen without the necessity of complicated changes in the manufacturing apparatus between the manufacture of successive elements and/or screens.

Other objects of the invention will in part be obvious and will in part appear hereinafter.

The invention accordingly comprises the process involving the several steps and the relation and order of one or more of such steps with respect to each of the others which are exemplified in the following detailed disclosure, and the scope of the application of which will be indicated in the claims.

For a fuller understanding of the nature and objects of the invention, reference should be had to the following detailed description taken in connection with the accompanying drawing wherein:

The figure is a diagrammatic perspective view of an apparatus illustrating performance of a process practiced in accordance with the present invention.

SUMMARY OF THE INVENTION

It has now been discovered that color screen elements exhibiting a high degree of optical acuity and particularly adapted for use in photographic processes, of both the conventional and diffusion transfer type, particularly additive multicolor photographic processes, may be expeditiously prepared, in general, by coating, on a surface of a support, a plurality of photoresponsive layers. Each photoresponsive layer is selectively exposed to electromagnetic radiation actinic to the layer in order to provide to the layer a plurality of discrete exposed areas, in screen relationship, and at least one of the plurality of photoresponsive layers is exposed by periodically contacting such layer with a defined pattern of electromagnetic radiation actinic to such layer preferably radiation of high intensity and short duration, to provide a desired plurality of exposed areas of that layer separated from each other as determined by the exposure pattern. Each photoexposed layer is dyed as a function of its point-to-point degree of exposure to provide a series of chromatic filter elements particularly adapted to filter selected, or predetermined, wavelengths of incident electromagnetic radiation in accordance with its radiation absorbability.

DESCRIPTION OF THE PREFERRED EMBODIMENT

In a preferred embodiment of the present invention, a transparent support member, most preferably a flexible transparent polymeric web material, is successively coated with photoresponsive layers particularly adapted to pro-

vide for the formation of a photoresist, as a function of exposure to electromagnetic radiation actinic to the layers, as for example, potassium, sodium, or ammonium dichromate sensitized gelatin, or photosensitized albumin, casein, gum arabic, polyvinyl alcohol, or any other photoresist-forming, radiation-sensitive polymers known in the art as adapted for employment for the production of resists by photomechanical means. Prior to the coating of the next succeeding photoresponsive layer, each preceding layer is selectively exposed, as detailed hereinafter, to radiation actinic to such layer in order to provide a plurality of discrete exposed areas to the layer. The unexposed portions of the layer are then removed by contact with a solvent for same, e.g., water, and the remaining areas, now constituting a resist, are dyed a selected color thereby providing a series of chromatic optical filter elements adapted to filter selected wavelengths of incident electromagnetic radiation.

In the preferred embodiment described above, exposure of the photoresponsive layer next contiguous the support is accomplished by periodically contacting such layer, in regular sequence, directly or less preferably through the transparent base with a defined pattern, that is, corresponding substantially to the chromatic filter element to be formed, of incident preferably high intensity, short duration actinic radiation, to provide the desired plurality of exposed areas to that layer. Exposure of the second and succeeding layers may then be accomplished by the preceding technique of periodically contacting the layers with actinic radiation, in a selected pattern, for example, the above-described flashing or pulsing technique, directly or more preferably through the transparent base whereby the previously-formed optical filter elements may operate as a mask, to provide the desired number of series in side-by-side screen relationship. Most preferably, however, the second and succeeding layers, except for the terminal layer, are exposed by periodically contacting such layers successively through the transparent support at an angle to the longitudinal axes of the previously-formed filter elements and, where the preferred trichromatic color screen is produced, the second exposure will most preferably be accomplished by periodically contacting the second layer to provide a pattern of parallel lines at about a 90° angle to the longitudinal axis of, and as masked by, the first-formed pattern of parallel line filter elements.

The terminal exposure in the preferred embodiment is accomplished by diffuse radiation traversing through the transparent support and exposing the terminal photoresponsive layer as masked by the previously-formed optical filter elements.

In accordance with one procedure, color coupling techniques may be employed to provide the requisite registered color images forming the required chromatic filtered elements. According to such techniques, one or more, generally gelatinous, selectively photoresponsive, silver halide strata containing the desired latent image definition are suitably, directly or reversibly, developed to color images, as a function of exposure, by selective intimate contact between one or more color developing agents and one or more color formers or couplers disposed in the respective strata to provide the requisite color image formation and definition.

In accordance with a second procedure, a preformed dye disposed in the respective strata may be selectively removed and/or bleached as a function of the point-to-point degree of exposure to provide the requisite chromatic filter element formation.

Thus, in accordance with the present invention, a method for manufacture of a color screen by selectively exposing to light a portion of a photoresponsive layer adjacent to a support base is provided whereby the exposure pattern is transformed into a screen pattern composed of two or more optical filter elements rendering a screen useful, for example, for photographic color processes and wherein exposure of the photoresponsive layer is carried out by a periodic contact flashing tech-

nique employing a source of preferably high intensity radiation which repetitively forms the screen pattern either one element at a time or, alternatively, a plurality of elements at a time. In the process of this invention a photo-responsive layer may be coated on a continuous transparent web base. The web may then be passed under a source of radiation which is periodically or successively activated or flashed as the web moves in the direction of its longitudinal axis; the period of and the rate of flash being controlled by source electronic switching which activates a mechanical or electro-optical shutter using a high intensity source emitting continuous radiation. Such switching devices are designed to act in synchronization with the transverse movement of the web. In this manner, an exposure pattern is superimposed on the photo-responsive layer which may then be processed to produce a series of filter screen elements as detailed above.

Subsequent to formation of the first series of chromatic filter elements, second and succeeding series of filter elements may be provided by recoating the web with additional photoresponsive layers, and repetition of the flash or pulse exposure of the layers, preferably through the web in a direction either parallel and displaced from or at angles to the first set of elements, and processing the exposed coatings to completion. Alternatively, the terminal coating or second coating, if only a two-color screen is contemplated, may be given an overall or fill-in exposure through the previously-formed filter elements.

A detailed description of a preferred embodiment for formation of a three-color screen follows.

Referring to the figure, there is shown a diagrammatic perspective view of an apparatus particularly adapted for selectively exposing and treating portions of a photo-responsive layer, in accordance with a preferred embodiment of the process comprising the present invention, to provide for the manufacture of a color screen element.

Here there is shown a freely rotatable cylindrical web supply drum 1 supplying a continuous web 2 comprising a transparent film base 3, such as a cellulose derivative film base, for example, a cellulose triacetate film base, which may have subcoated thereon an adhesive lacquer layer, such as a nitrocellulose lacquer layer (not shown), which has overcoated thereon a selectively photoresponsive, preferably polymeric, layer 4, such as an approximately 4 micron (dry weight) thick potassium or ammonium dichromate sensitized, photohardenable gelatin layer.

In carrying out the instant embodiment, web 2 continuously passes over roll guides 5 and guide plate 6 where, at the latter position, it is periodically exposed to electromagnetic radiation 7, actinic to photoresponsive layer 4, successively incident on photoresponsive layer 4 in a pattern substantially corresponding to the chromatic filter element to be formed, for the contact duration necessary to provide, to photoresponsive layer 4, exposed areas corresponding to the chromatic filter element to be formed. As illustrated in the figure, the exposing electromagnetic radiation may be provided, at the exposure station, by radiation 7 emanating from source 9, which emits a continuous stream of high intensity radiation, which passes through aperture 8 and is periodically interrupted by optical chopper blade 40 powered by synchronous motor 41 producing a series of pulses of radiation of short duration which expose photoresponsive layer 3 coated on moving web 4 in the stated pattern. The thus produced radiation will be suitably monitored or controlled to provide the selected pattern of periodic incident radiation corresponding to the desired chromatic filter element to be formed, for example, as illustrated, by the interpositioning of aperture plate 8 so constructed as to provide radiation 7 incident on photoresponsive layer 4 conforming to the desired filter element parameters. Guide rolls 5 may provide motor power to assist the substantially uniform movement of the web through the exposure area, or station, the means to motivate these rollers, in such instances, for example, motors, pulleys, gears,

etc., not being shown as they would be obvious to one skilled in the art.

Subsequent to photoexposure, web 2 may be processed by transporting it into a wash tank 10 wherein the photo-exposed and thereby differentially hardened gelatin of photoresponsive layer 4 is contacted with agitated water 11, maintained at a temperature within the range of about 80 to 140° F., for a time interval of about 3 to 60 seconds, in order to effect removal of unexposed, and thus unhardened, gelatin, in accordance with the scanned exposure pattern.

Web 2 may then be transported into another wash tank 12 wherein the hardened gelatin grid is subjected to a current of water 13 flowing counter to the path of web transport, in order to remove any possible residual debris and unhardened gelatin.

Continuous web 2 may then be transported through a dye tank 14, containing dye solution 15 comprising a dye substantive to the gelatin grid, for example, a primary red color acid dye, in order to provide the desired coloration to the first-formed optical filter elements. The contact time between travelling web 2 and dye solution 15 generally should be of the order of about one minute, after which time, web 2 may be directed through another wash tank 16 containing cold water 17 in order to effect removal of any residual or excess dye.

Web 2 may then be dried by passage through a drying chamber 18, containing suitable air circulating mechanisms or radiant energy devices, such as infrared elements, adapted to effect drying of web 2. Subsequent to effecting drying of web 2, the same may be spooled on a cylindrical web storage drum 19 for subsequent operations. The transport of web 2 may be effected by electric drive motor 23 providing positive rotation of web storage drum 19, for example, through an appropriate transmission comprising gears, drive shaft and step clutch (not shown) according to procedures well-known in the art.

Alternatively, the web may be continuously processed to completion of the multicolor screen element by coating the first optical filter element containing surface of the web with an adhesive lacquer layer. Subsequent to substantial drying of the lacquer coating, the web may then be overcoated with a second photoresponsive dichromate sensitized gelatin layer.

The web is again transported through the same or a similar apparatus, as would be appropriate for use in continuous monitoring operations, and is periodically exposed, as described hereinbefore, with radiation incident on and traversing through on transparent support 3. In general, the pattern of incident radiation employed will be such as to preferably provide exposed areas to the second photoresponsive layer and, ultimately, chromatic filter elements having a longitudinal axis at an angle to, and preferably at an angle approximating 90° to, the longitudinal axis of the previously formed chromatic filter elements, where such previously formed chromatic filter elements possess a preferred conformation comprising a plurality of substantially parallel equidistant lines. Where desired, however, the exposed areas may also be provided as a plurality of substantially parallel lines equidistant from each other and in juxtaposition to the previously formed chromatic filter elements. The filter lines or elements formed during such preferred first exposure and processing may serve to mask radiation from those areas of the photoresponsive layer directly below the first set of elements and thus facilitate the formation of a selected pattern.

The continuous web may then be processed, dyed, preferably with an acid dye of green coloration, and dried in accordance with the previously detailed description.

At this point in the process, the web, now containing a first and second series of optical filter elements, may be spooled on a storage cylinder for subsequent operations and/or employment.

In the alternative, a third series of optical filter elements may be immediately formulated by coating the external surface of the second optical filter element series with an adhesive lacquer and overcoating the lacquer coating with a third photoresponsive dichromate sensitized gelatin layer.

The web is again transported through the same or similar apparatus and exposed to continuous collimated non-pulsing radiation incident on the external surface of the web. Exposure of the third photoresponsive layer is accomplished by radiation traversing through the film base and, masked by the previously formed optical filter elements, thus provides formation of a third series of photo-exposed areas, in apparent contiguous relationship to the first and second series of optical filter elements.

The continuous web may then be processed, dyed, preferably with an acid dye of blue color, dried and stored, in accordance with the aforementioned procedures, thus providing a third series of optical filter elements in screen relationship to the first- and second-formed filter element series with respect to actinic radiation traversing through the filter screen perpendicular to the axis of its main plane.

Optionally, the thus-formed multicolor screen may be overcoated with a protective polymeric composition, such as nitrocellulose, cellulose acetate, etc., prior to the external surface thereof having, for example, a panchromatically sensitized photographic emulsion or a diffusion transfer print-receiving layer applied thereto.

As shown in the drawing, the interruptor means, the optical chopper, is located next adjacent to the web, i.e., between the web and aperture plate 8. Optionally, the interruptor may also be located between the source and the aperture 8.

In the preferred embodiment using the stated dichromated gelatin ~ 0.5 joule/sq. in. is adequate to harden the selected areas of such material.

Photographic multicolor screens containing 1000 lines to the inch are of very acceptable quality. The width of each line is then approximately 0.0010 inch and the effective width in this embodiment due to the directional relationship of the pattern with the movement of the web is 0.0014 inch for aperture slits at 45° to the normal. A web moving at a speed of one inch per second will during that pulse time move no more than 0.0004 inch for a pulse duration of about 0.3 to 0.4 millisecond which when subtracted from the effective width yields a desired width of 0.0010 inch for the screen element. For screens of finer elements, shorter pulse durations may be provided. Additionally, the web transport speed and/or the parameters of the control switches may be adjusted to give shorter pulses. A suitable commercially available control is the EG&G TM-11 trigger module which operates at 110 v.a.c. The rate of production which results from the method of this system is significantly superior to the production rate of other methods. A linear rate of five feet per minute in any reasonable width may be obtained for an overall yield of 10 to 15 sq. feet per minute.

Other combinations of elements to produce apparatus suitable for practicing the process of this invention include those employing high intensity arc and filament lamps as radiation sources and electro-optical shutter devices in place of the control switch or rotating chopper blade, all designed to produce a periodically flashing source of radiation.

Thus, as mentioned above, the technique of this invention may also be successively used to provide a simultaneous plurality of exposed areas to a photoresponsive layer. For example, a plate containing a plurality of apertures such as slits forming the desired pattern may be interposed between the pulsing radiation source and the moving web comprising the photosensitive material. This approach may also be extended to expose a large area of photosensitive material at a single time where multiple light sources are used to provide sufficient covering power

for the surface of the aperture plate. In all cases, then energy available from the light source should be sufficiently high to provide adequate exposure of the photosensitive layer during the short pulse time relative to the movement of the web. By choosing the proper parameters, it is possible to expose a moving web to a source of short duration and high intensity such that sufficient exposure is obtained with substantially no blurring due to the movement of the web.

As indicated above, it will be recognized that many other combinations of electromagnetic radiation sources, photoresponsive substances and processing steps may be used in accordance with the present invention. For example the techniques of this invention have equal applicability to the manufacture of the stated color screens using photopolymerization systems. Similar steps and combinations of processes, as those shown above, i.e., exposure, dyeing, and washing, may be carried out with photoresponsive elements having a radiation-sensitive layer comprising a polymerizable monomer and a suitable photoinitiator for the polymerization reaction. Under the influence of actinic radiation, the photoinitiator becomes activated and induces the polymerization of the monomer.

Treatment with a suitable solvent that dissolves, for example, the nonpolymerized material in the unexposed areas but not the polymer in the exposed areas, will ultimately result in a series of color screen elements similar to those produced by the use of dichromated gelatin. With regard to such systems, reference is made to Light Sensitive Systems: Chemistry and Application of Non-silver Halide Photographic Processes, Jaramir Kosar, 1965, and specifically to Chapter 5.

In addition, the employment of photochemical dye formation and photochemical dye destruction systems in the present invention are also selectively available in accordance with the desires of the process operator.

The support or web may comprise any of the various types of ridged or flexible supports, for example, glass, paper, metal, polymeric films of both the synthetic type and those derived from naturally occurring products, etc. Especially suitable materials, however, comprise transparent synthetic polymers such as polymethacrylic acid, methyl and ethyl esters; vinyl chloride polymers; polyvinyl acetals; polyamides such as nylon; polyesters such as the polymeric films derived from ethylene glycol terephthalic acid; polymeric cellulose derivatives such as cellulose acetate, triacetate, nitrate, propionate, butyrate, acetate-butyrate, or acetate propionate; polycarbonates; and polystyrenes.

The line depth exposure of the photoresponsive layers in any of the systems detailed may be accurately controlled by suitably varying the intensity and/or time of the incident radiation.

It will be readily recognized that the instant processes are particularly adapted for use in the continuous photo-mechanical production of color screen elements by continuous processing of a travelling web according to the procedure detailed in explanation of the drawings. This continuous processing may be such as to provide completion of the multicolor screen element as a photographic film unit itself or, where desired, the processing may be interrupted at any stage for further operations at a subsequent time. The web itself may be continuous or discontinuous and may be continuously or intermittently processed, as desired.

For preparation of the preferred three-color additive screens, the exposed area of each photoresponsive layer comprises about one-third of the area of that layer. Exposure of the second photoresponsive coating is accomplished by incident radiation adapted to provide exposure of about one-third of the area of the second coating, the filter elements positioned most preferably substantially adjacent or in juxtaposition, respectively, to the 75 first-formed chromatic filter elements. By proper choice

of the photosensitive system or of the incident radiation, the first filter element may be opaque to subsequent exposure radiation. It may then be desirable to overlap the second set of images on the first set of elements, when such is desired to be parallel to the first set, without creating, for example, a black band due to the presence of superimposed areas of primary additive colors. Variables in the manufacture of the second set of elements will then cause less variation in the width of the second elements than would be encountered without this intentional overlap. Furthermore, intentional overlap can prevent small gaps between the first and second elements; these gaps, even if they are filled in with the third color, are disadvantageous in the photographic utilization of the color screen.

As previously stated, the color screen elements of the present invention are particularly adapted to be employed as elements of a photographic film unit. Specifically, the instant color screen elements, exhibiting a high degree of optical acuity, are particularly adapted for use in multicolor photographic processes, both of the conventional and diffusion transfer type, especially additive multicolor photographic processes.

Additive color photographic reproduction may be produced by exposing a photoresponsive material, preferably a photosensitive silver halide emulsion, through an additive color screen having filter media or screen elements, each of an individual additive color such as red, blue or green, and by viewing the resultant photographic, e.g., silver, image, subsequent to development, through the same or a similar screen element.

Although for photographic purposes, a photosensitive emulsion may be positioned on the rear side of a carrier retaining the color screen, for practical purposes it is preferred to position the emulsion on the color screen side of the element in order to maximize color saturation.

After exposure of the photoresponsive component of the photographic film unit, the resultant exposed element may be processed in the same manner as black-and-white photographic film is conventionally processed, without regard to the filter screen which is preferably spaced between the carrier and the emulsion component, especially where the filter screen is protected from processing composition contact by a protective polymeric composition.

Where positive photographic image formation is desired, that is, an image provided in terms of unexposed portions of the emulsion, reversal processing may be employed in its conventional manner, or a conventional "direct positive" emulsion may be employed, or the positive image may be provided by diffusion transfer processing.

In multicolor additive diffusion transfer processes, a latent image provided, as indicated above and contained in the exposed, photosensitive, preferably gelatinous, silver halide emulsion, is developed and, substantially contemporaneous with development, a soluble silver complex is obtained, for example, by reaction of a silver halide solvent with unexposed and undeveloped silver halide of the emulsion. The resultant soluble silver complex is, at least in part, transported in the direction of a suitable print-receiving element, and the silver of the complex precipitated in such element to provide the requisite positive image definition. The resultant transfer image may be viewed through the same, or a similar, additive color screen element which is suitably registered with the silver transfer image carried by the print-receiving layer.

For use in diffusion transfer multicolor additive photographic systems, the preferred film units have a panchromatically sensitized photographic emulsion coated on the external surface of the print-receiving layer, which is itself coated on a surface of the color screen, either with or without a stripping layer positioned intermediate the print-

receiving layer and emulsion layer, to facilitate separation of the emulsion layer subsequent to transfer processing. Employing the instant preferred integrally constructed film unit allows exposure of the emulsion to be accomplished through the color screen, including through a transparent supporting member if present, and diffusion transfer formation of the positive silver image in the print-receiving layer contiguous the color screen employed during exposure. This embodiment accordingly obviates the necessity of registering a color screen with the resultant photographic image, for viewing purposes, in that the screen employed for exposing may also be employed for viewing and is automatically in register with the transfer image. The stripping layer itself may comprise a polymeric substance, such as hydroxyethyl cellulose, cellulose acetate, hydrogen phthalate, etc.

Diffusion transfer additive photographic processes are disclosed in U.S. Patents Nos. 2,614,926; 2,726,154; 2,944,894; and 2,992,103, issued Oct. 21, 1952; Dec. 6, 20 1955; July 12, 1960; and July 11, 1961, respectively.

The image-receiving layer may itself be comprised of one or more strata of a permeable substantially transparent material. As examples of image-receiving materials of such a nature, mention may be made of: regenerated cellulose; polyvinyl alcohol; partially hydrolyzed polyvinyl acetate; sodium alginate; cellulose ethers, such as methyl cellulose or other cellulose derivatives, such as sodium carboxymethyl cellulose or hydroxyethyl cellulose; proteins, such as gelatin or glue; carbohydrates, such as gums and starches; and mixtures of such materials, as for example, polyvinyl alcohol and gelatin, where they are compatible.

It will be recognized that the silver-receptive stratum should be so constituted as to provide an unusually vigorous elemental silver precipitating environment which causes the elemental silver deposited therein, in comparison with the amount of silver developed in the silver halide photosensitive layer, to possess very high covering power, that is, opacity per given mass of reduced silver.

Especially suitable as silver precipitating agents are the metallic sulfides and selenides, these terms being understood to include the selenosulfides, the polysulfides, and the polyselenides. Preferred in this group are the so-called "heavy metal sulfides." For best results it is preferred to employ sulfides whose solubility products in an aqueous medium at approximately 20° C. vary between 10^{-23} and 10^{-30} and especially the salts of zinc, cadmium and lead. Also suitable as precipitating agents are heavy metals such as silver, gold, platinum, palladium, and mercury, and in this category the noble metals are preferred and are generally provided in the matrix as colloidal particles.

As disclosed in U.S. Patent No. 2,698,244, issued Dec. 28, 1954, diffusion transfer processing may be effected by disposing a liquid processing composition in a rupturable container so positioned in regard to the appropriate surface of a silver halide emulsion that, upon compression with a spreader sheet, a substantially uniform layer of processing composition is distributed over the surface of said photosensitive emulsion, positioned distally from the image-receiving layer. The processing composition may be one of the film forming processing compositions disclosed in U.S. Patent No. 2,543,181, issued Feb. 27, 1951. It may comprise, for example, a developing agent such as hydroquinone, an alkali such as sodium hydroxide, a silver halide complexing agent such as sodium thiosulfate, and a high molecular weight film-forming thickening agent such as sodium carboxymethyl cellulose. All these materials are preferably in aqueous solution. These photographic agents are preferably contained in solution in the processing liquid prior to the application thereof, but they may be in part or wholly added to the processing composition as it is spread between the spreader sheet and the photosensitive silver halide emulsion, said agents being 70 so located on or adjacent to the surface of one or both of

said layers as to be dissolved by or otherwise interacted with the liquid agent when the latter wets said surface.

In carrying out the aforementioned transfer process, the photosensitive silver halide emulsion is photoexposed to form therein a latent image. A substantially uniform distribution of processing composition is distributed on the external surface of said emulsion, as for example, according to the previously-described procedure. Processing composition reagents permeate into the photosensitive emulsion, developing the latent image contained therein according to the point-to-point degree of exposure of said emulsion. Substantially contemporaneous with the development of the latent image, an imagewise distribution of soluble silver complex is formed from unexposed and unreduced silver halide within said emulsion. At least part of said silver complex, solubilized, is transferred, by imbibition, to the print-receiving stratum. The transferred silver complex is reacted to provide a positive, reversed image of the latent image. Subsequent to formation of the positive image in the image-receiving layer, dissociation of said layer from the emulsion layer may be effected.

It must be noted that abrasion-resistant properties may be provided to the image-receiving layer, by the inclusion therein of deacetylated chitin, as disclosed in U.S. Patent No. 3,087,815, which alleviates the necessity of subsequently overcoating the external surface of image-receiving layer with a transparent abrasion-resistant water-insoluble plastic, to prevent laceration and resultant degradation of the positive image, subsequent to removal of the emulsion from contact therewith.

The concentration of deacetylated chitin disposed in the image-receiving layer may be varied over a wide range according to the degree of rigidity desired, during and subsequent to processing, and the thickness and character of the image-receiving stratum employed.

Other materials may be substituted for those used in the foregoing photographic process and the proportions may be varied to an appreciable extent. For example, the film-forming material in the processing composition which imparts the desired viscosity to the latter may be any of the high molecular weight polymers which are stable to alkali and which are soluble in aqueous alkaline solutions. For example, such other plastics as hydroxyethyl cellulose, polyvinyl alcohol, and the sodium salts of polymethacrylic acid and polyacrylic acid may be used. The plastic is preferably contained in the processing composition in sufficient quantity to impart to the composition a viscosity in excess of 1,000 centipoises at a temperature of approximately 20° C. Preferably, the viscosity of the processing composition is of the order of 1,000 to 200,000 centipoises.

Other developing agents may be used, for example, one of the following: p-aminophenol hydrochloride; bromohydroquinone; chlorohydroquinone; diaminophenol hydrochloride; diaminophenol dihydrochloride; toluhydroquinone; monomethyl-p-aminophenol sulfate; a mixture consisting by weight of $\frac{1}{2}$ hydroquinone and $\frac{1}{2}$ p-hydroxyphenylaminoacetic acid; and a mixture consisting by weight of $\frac{1}{4}$ hydroquinone and $\frac{3}{4}$ p-hydroxyphenylamino-acetic acid.

To form the soluble silver complex, such other complex-forming substances as sodium thiocyanate, ammonium thiocyanate and ammonia may be employed.

The preferred silver halide type photographic emulsion, employed for the production of the photographic film unit, may be prepared by reacting a water-soluble silver salt, such as silver nitrate, with at least one water-soluble halide, such as ammonium, potassium or sodium bromide, preferably together with a corresponding iodide, in an aqueous solution of a peptizing agent such as a colloidal gelatin solution; digesting the dispersion at an elevated temperature, to provide increased crystal growth; washing the resultant dispersion to remove undesirable reaction products and residual water-soluble salts by

chilling the dispersion, noodling the set dispersion, and washing the noodles with cold water, or, alternatively, employing any of the various floc systems, or procedures, adapted to effect removal of undesired components, for example, the procedures described in U.S. Patents Nos. 2,614,928; 2,614,929; 2,728,662, and the like; after-ripening the dispersion at an elevated temperature in combination with the addition of gelatin and various adjuncts, for example, chemical sensitizing agents and the like; all according to the traditional procedures of the art, as described in Neblette, C. B., *Photography—Its Materials and Processes*, 6th Ed., 1962.

Panchromatic optical sensitization of the emulsion's silver halide crystals may then be accomplished by contact of the emulsion composition with an effective concentration of panchromatic optical sensitizing dye or dyes; all according to the traditional procedures of the art, or described in Hamer, F. M., *The Organic Dyes and Related Compounds*.

Subsequent to optical sensitization, any further desired additives, such as coating aids and the like, may be incorporated in the emulsion and the mixture coated and processed according to the conventional procedures known in the art.

The photoresponsive material of the photographic emulsion will, as previously described, preferably comprise a crystal of a compound of silver, for example, one or more of the silver halides, such as silver chloride, silver iodide, silver bromide, or mixed silver halides, such as silver chlorobromide or silver iodobromide, of varying halide ratios and varying silver concentrations.

As to the binder for the photoresponsive material, the aforementioned gelatin may be, in whole or in part, replaced with some other natural and/or synthetic colloid material such as albumin; casein; or zein; or resins as a cellulose derivative, as described in U.S. Patents Nos. 2,322,085 and 2,327,808; polyacrylamides, as described in U.S. Patent No. 2,541,474; vinyl polymers such as described in U.S. Patents Nos. 2,253,078; 2,276,322; 2,276,323; 2,281,703; 2,310,223; 2,311,058; 2,311,059; 2,414,208; 2,461,023; 2,484,456; 2,538,257; 2,579,016; 2,614,931; 2,624,674; 2,632,704; 2,642,420; 2,678,884; 2,691,582; 2,725,296; 2,753,264; and the like.

It may be found that after the dyeing of layers of monochromatic filter elements, there may tend to remain, even after rinsing, a molecular film of the dye over the areas previously stripped. Under these circumstances, it may be preferred to forcibly separate the excess dye from the unexposed areas and this may be accomplished by directing vigorous air blasts in the direction parallel to the long side of the particular areas being operated on.

It is desirable, of course, that the adhesion of the carrier, the three monochromatic filter layers, etc., should be very secure so that the individual structures will remain bonded during the manufacture and processing of the finished product, and further that there will be subsequently no mechanical separation of the various layers which will create optical and mechanical difficulties.

Under these circumstances, it is desirable that adhesive or lacquer layers be interposed between respective layers and filter elements. The adhesive layer selected should be one which does not deleteriously interfere with the transparency of the final product, and yet provides sufficient adhesive capacity so as to allow vigorous treatment of the film unit during and subsequent to its production. The aforementioned nitrocellulose has been found to be a highly desirable bonding agent, although other adhesive known in the art for the instant purposes may be employed, where desired.

The bond obtained throughout the entire unit by this invention should be sufficient to withstand the vigorous treatment such as air blasting and heat to which the unit may be exposed. Moreover, there should be no local separation of the various layers during mechanical treatments that would cause spots, particularly on magnification.

Various colors and numbers of colors may be used in this invention but the preferred system is a tri-color arrangement of the three primary colors, red, green and blue. A four-color system such as red, green, violet-blue and orange-yellow could be used also, by a sequential series of exposures effecting approximately one-fourth of the respective photo-responsive area providing formation of optical filter elements comprising a single selected color, followed by, for example, a fourth overall exposure, in accordance with the teachings of the instant disclosure. Furthermore, it will be recognized that, in accordance with the instant disclosure, a plurality of chromatic filter element series may be provided, the number of series being solely determined by the optical parameters of the resultant color screen desired.

In the description herein, each color series of filter elements has been described as covering that part of the total area in proportion to the total number of colors used, i.e., in the tri-color system, each color occupies one-third of the total area. This may vary quite widely before having a noticeable effect to the observer and, in fact, may be compensated by changing the intensity of the colors. In actual practice, if one dye is of greater intensity than the others, a deliberate compensation may be made by reducing the total relative area of the intense color. The aspect of relative areas is well known in the art so that when relative areas are used in this application, it is intended to include the variances which the art would recognize as being successful.

Although acidic or basic dyes may be used in the present process, it is desirable to use acidic dyes which are generally considered to be more durable and to possess better tone. Various suitable wetting agents may also be added to the dye solutions to further insure a thorough penetration of the dye into the desired areas.

As examples of dyes for effecting coloration of the optical filter units, mention may be made of acid red dyes such as Acid Reds C.I. 1 and C.I. 34, which may be mixed with Direct Red C.I. 24, Acid Yellow C.I. 36 or Direct Yellow C.I. 4; acid green dyes such as Acid Green Pina (trade name of Farbwerke Hoechst Ag., Frankfurt, Germany, for a triphenyl methane dye) which may be mixed with the above yellow dyes; and acid blue dyes such as Acid Blue C.I. 27.

Since certain changes may be made in the above product, process and apparatus without departing from the scope of the invention herein involved, it is intended that all matter contained in the above description shall be interpreted as illustrative and not in a limiting sense.

What is claimed is:

1. A process for the continuous manufacture of a chromatic color screen composed of a plurality of chromatic light filtering element series, said filter element series comprising red, green and blue colored filter elements, said elements arranged in the form of separate discrete areas, which comprises:
  - (a) coating on a surface of a support a first photo-responsive layer;
  - (b) selectively exposing about one third of said photo-responsive layer to electromagnetic radiation actinic to said layer to provide a plurality of discrete exposed areas, in parallel relationship, separated from each other, said exposing being carried out by means of an exposure system comprising, in essence, a

- source for said electromagnetic radiation, a fixed aperture plate, the aperture of said plate being substantially the same shape as the desired filter elements, and interruptor means adapted to provide a series of pulses of radiation of short duration;
- (c) removing the unexposed portions of the photo-responsive layer;
  - (d) dyeing the exposed areas, to form first colored filter elements;
  - (e) coating a second photoresponsive layer on said first filter elements;
  - (f) selectively exposing about one-third of said second photoresponsive layer to electromagnetic radiation actinic to said layer to provide a plurality of discrete exposed areas, in parallel relationship at about a 90° angle to the longitudinal axis of the first formed pattern of colored filter elements, said exposing being carried out by means of an exposure system comprising, in essence, a source for said electromagnetic radiation, a fixed aperture plate, the aperture of said plate being substantially the same shape as the desired filter elements, and interruptor means adapted to provide a series of pulses of radiation of short duration;
  - (g) removing the unexposed portions of the photo-responsive layer;
  - (h) dyeing the exposed areas to form second colored filter elements;
  - (i) coating a third photoresponsive layer on said first filter elements;
  - (j) selectively exposing about one-third of said third photoresponsive layer to electromagnetic radiation actinic to said layer to provide a plurality of discrete exposed areas;
  - (k) removing the unexposed portions of the photo-responsive layer; and
  - (l) dyeing the exposed areas to form third colored filter elements.
2. The process as defined in claim 1 wherein said interruptor means comprises a rotating optical chopper blade.
3. The process as defined in claim 1 wherein said interruptor means are positioned between said aperture plate and said web.
4. The process as defined in claim 1 which includes the step of coating a diffusion transfer print-receiving layer on the external surface of said chromatic filter elements.
5. The process as defined in claim 4 which includes the step of coating a photographic emulsion layer on the external surface of said receiving layer.
